PACKAGING MOLTEN SOAP

Ralph H. Potts, Chicago, Ill., assignor to Armour and Company, Chicago, Ill., a corporation of Illinois

Application April 24, 1933, Serial No. 667,569

7 Claims. (Cl. 226—93)

The present invention relates to an improved method of commercially packaging soaps which are liquid when hot and which become solid when cold. Such soaps are ordinarily cooled and caused 5 to set to a hard condition in the factory, molded or cut into cake or bar form, wrapped and then sold to the trade.

My invention is characterized by the fact that the hot liquid soap is flowed directly from the 10 soap kettle or crutcher by way of suitable filling machines into foldable paper cartons, lined or unlined, and therein subjected to chilling to superficially harden or congeal the soap to an extent adequate to maintain the shape in the carton, 15 when properly supported, leaving ultimate setting and hardening throughout to take place solely on the dealer's shelves, thus eliminating time-consuming, wasteful, operations of manufacture, assuring uniform distribution of the filler and conserving volatile ingredients such as perfumes. 20

My improved method reduces the time of manufacture from the crutcher to shipment by more than 99%, that is to say, from a week or ten days to a matter of minutes. Thereby is reduced almost to a vanishing point the labor cost, investment, floor space for cooling and drying, cutting, molding and rehandling of scrap. The cost of 25 producing the soap practically ends with the crutcher according to my method, whereas under former practice the manufacture of the product 30 after the crutcher stage consumed many days.

In order that the relation of the present invention to the soap making art may be readily appreciated, a brief résumé is in order of the procedure which has been practically universal in 35 the art of soap manufacture for generations.

There are two general classes of soaps, "milled" soap and "framed" soap, of which toilet and laundry soaps are respectively typical. Inasmuch 40 as this invention does not have to do with milled soap, a detailed description of that method of production is omitted.

In the production of soap by "framing" the meat soap is pumped from the kettles into crutchers 45 or mixing kettles where various fillers are incorporated, such as sodium silicate and soda ash, with perfumes where used. The liquid mass is then run into large built-up frames with removable sides, each having a capacity of 1300 50 pounds. In the frames the soap is allowed to stand for from four to six days to allow the contents to cool and set sufficiently to permit the sides of the frame to be removed. Thereafter the soap mass is allowed to stand another three 55 to five days to permit further cooling and setting

throughout. The soap block is then, by means of a slabbing machine, sliced into slabs about four feet long by fifteen inches wide and of a thickness corresponding to the size of cake desired. The slabs are then transferred to a cutting machine 5 for transverse and longitudinal cutting into cakes. The still soft cakes are then placed on racks in a drying chamber where they are skin dried by moving warm air, after which the cakes can be pressed in dies, ready for wrapping. 10

Incident to framing and cutting there is usually from 30% to 40% waste and scrap which must be remelted and reworked, with a loss of the original filling ingredients. Moreover, a disadvantage incident to the framing of soap is the 15 tendency of the filler ingredients to settle to the lower part of the mass and to work to the surface, presenting a mottled appearance, wherefore the resultant cakes of soap are not uniform as to 20 filler composition and the mottled exterior entails much scrap.

The time consumption, floor space, labor, investment and waste have been recognized as formidable disadvantages of laundry soap manufacture and various devices have been tried 25 to overcome them such as small frames to facilitate cooling, water-cooled frames to save time, individual cake or bar frames, extrusion of the soap into chilled brine, individual molds for chilling the soap before packaging, etc. None of 30 these expedients have been found practicable or have been commercially adopted. Considerations of waste, expense, labor, investment and unfitness for mass production have caused their 35 abandonment and all soap manufacturers are 40 today employing the old method of framing, notwithstanding its recognized disadvantages, for the reason that none of the proposed changes in method have been found to be operable in large scale soap manufacture.

According to my invention the soap is run from the crutcher into a suitable filling machine. It is then flowed into foldable paper cartons, each of a size to contain one cake or bar of soap. The cartons are closed either by hand or by a 45 suitable machine and are then superficially and quickly chilled by passing them through a refrigerating channel whereby the exterior of each filled carton is sufficiently chilled to cause superficial congealing, setting and hardening of the 50 contents. During such superficial chilling the sides of the filled carton are supported against deformation as by the walls of the refrigerating channel or other external support. The still 55 soft but superficially hardened filled cartons are 55

then arranged in such juxtaposition that they mutually support each other, as by snug packing upon a shelf or in a shipping case and the final hardening and setting throughout takes place after packing for shipment.

The liquid soap having been transferred directly from the crutcher into the cartons, the filler ingredients are uniformly distributed through each cake and the perfume has no opportunity to escape. The cakes of soap reach the dealer in fresh, sanitary and attractive condition. The soap cake having first been chilled on the exterior, it is impossible for the ingredients to work to the surface to cause a mottled appearance. Warping, which is common to unconfined partially hardened soap cakes allowed to cure on the shelf of the dealer, is effectually prevented.

Not only is the soap as it reaches the consumer much better in appearance and quality than the soap produced by the old framing method but all the losses due to scrap and waste incident to framing, slabbing and slicing is avoided and the floor space during the weeks required for storage during the cooling and hardening in the frames is practically eliminated, inasmuch as the soap is superficially chilled and packed in the commercial cartons in less than ten minutes after it leaves the crutcher. It is customary for the larger soap manufacturers to have something like two million pounds of soap in the frames at all times undergoing original and supplemental cooling, slabbing, slicing and drying preliminary to forming into cakes for packaging. All of this storage space, labor and investment in soap undergoing manufacture is eliminated.

The details of mechanism for carrying out my improved method of soap manufacture form no part of the present invention, but in order to facilitate an understanding of the improved method a diagrammatic illustration of means employed for carrying out the same is set forth in the accompanying drawing, wherein the soap crutcher is indicated at 1, the contents of which are by means of the pump 2 conveyed to the filling machine 3 and by it introduced in measured quantity to the open cartons 4 supplied by the forming device 5 or from other source. When filled the cartons pass the carton-closing device 6 and thence to the belt conveyor 7 by which they are conveyed through the double wall channel 8 to the packing table 9. The channel 8 is refrigerated by brine or other suitable low temperature medium introduced to the inter-wall space at 10 and withdrawn at 11. The mechanical means thus diagrammatically shown is illustrative only of the principle embodied and not indicative of the structural nature of the instrumentalities employed in practicing the invention.

I claim:

1. The method of packaging soap which consists in flowing the soap while in a hot liquid condition into commercial cartons, superficially chilling to effect surface hardening only, and so packing that the filled cartons will mutually support each other against deformation while hardening throughout.

2. The method of packaging soap which consists in flowing the soap while in a hot liquid con-

dition into commercial cartons, subjecting the filled cartons to low temperature refrigeration sufficiently to merely surface harden the same while supporting the filled carton against deformation and arranging the filled surface-hardened cartons in mutual juxtaposition in laterally confined groups.

3. The method of treating soap to reduce expense of manufacture and preserve uniformity of product which consists in flowing the soap while in a hot liquid condition into commercial unit cartons, and superficially chilling the filled cartons whereby to shorten the time of solidification and thus prevent matters in suspension from working to the surface, and thereafter laterally confining a group of the still soft but superficially hardened filled cartons in such juxtaposition that they mutually support each other in shape during final complete hardening.

4. The method of treating freshly made soap containing filler ingredients in suspension which consists in flowing the hot liquid soap into commercial cake-molding cartons, and subjecting the filled cartons with their contents to superficial refrigeration whereby to prevent working of the filler particles to the surface, and thereafter laterally confining a group of the still soft but superficially hardened filled cartons in such juxtaposition that they mutually support each other in shape during final complete hardening.

5. The method of producing commercial soap cakes of uniform surface appearance from hot liquid soap containing filler ingredients in suspension which consists in flowing the hot liquid soap into individual commercial cartons, and quickly chilling the filled cartons to surface-harden the contents whereby to prevent the filler ingredients from separating out from the interior and affecting the exterior appearance of the cake, and thereafter laterally confining a group of the still soft but superficially hardened filled cartons in such juxtaposition that they mutually support each other in shape during final complete hardening.

6. The method of treating freshly made soap containing volatile ingredients which consists in flowing the hot liquid soap into commercial unit cartons, closing the cartons, subjecting the filled cartons with their contents to refrigeration at a low temperature to effect quick surface hardening only, and packing in juxtaposition to afford mutual support while slowly cooling throughout, thus preserving the shape of the units and preventing escape of the volatile ingredients.

7. The method of treating freshly made soap containing volatile ingredients and insoluble ingredients in suspension, which consists in flowing the hot liquid soap into commercial cake-molding cartons, closing the cartons, subjecting the filled cartons with their contents to refrigeration at a low temperature to effect quick surface hardening only, and then packing in juxtaposition to afford mutual support while slowly cooling throughout, thus preserving the shape of the cake units and preventing escape of the volatile ingredients and the working of the insoluble ingredients to the surface.

RALPH H. POTTS.
